UNITED STATES PATENT OFFICE.

HENRY H. HEWETSON, OF NEWTON CENTER, MASSACHUSETTS, ASSIGNOR TO BEACON OIL COMPANY, OF EVERETT, MASSACHUSETTS, A CORPORATION OF MASSACHUSETTS.

SOAKING-DRUM APPARATUS.

Application filed March 16, 1927. Serial No. 175,911.

This invention relates to containers for fluids under treatment under such conditions as to subject the containers to deterioration by use, particularly the containers for such fluids as very hot products of mineral oils or other chemically active vapors under treatment in refineries or industrial chemical plants.

Such vessels as the large steel soaking drums, for example, extensively employed in refineries to hold under high heat and pressure liquid oily products during the completion by time of the cracking of heavier hydro-carbon oils to more volatile products, such as gasoline, I have found to deteriorate under chemical reaction affecting only such parts of the containers as are in contact with the gases and vapors, as distinguished from the liquids, of the reacting contents. Under familiar practice, these vessels may be end-capped cylinders standing upright, having an internal diameter of as much as six feet, a height of the order of forty feet, and built up of plates from three to five inches thick so as to withstand internal pressures of much more than the usual pressure of about 400 pounds to the square inch with safety, at internal temperatures ranging from 500° to 900° F.

The hazards to life and property from explosions and fire flowing from the possibility of rupture of any of these containers are very great, and have heretofore led to frequent replacements when corrosive deterioration of the upper parts of the drums has progressed to something short of any dangerous extent. The massive nature of these vessels makes their replacement a matter of great expense of labor and idle time of apparatus, as well as for the metallic vessel itself. The factors leading to corrosion and pitting, which may be due to hydrogen, sulfur or other components of the contents under the severe conditions of heat and pressure, are of such a nature as to prevent their being avoided chemically or by any effective expedient of interior protection of the metal of so large a built-up structure as a soaking drum from the action of the corroding vapors by a permanent or replaceable lining.

This invention has as objects utilization of the observed immunity from corrosion of such parts of such containers as are continuously covered by liquid to prevent any necessity for replacing any part of the large vessel

itself; to provide a construction effective 55 against deterioration and operative for the necessities of the use of such apparatus which can be put into a safe condition when deteriorated without great delay or expense; and to provide for increasing the storage capacity 60 of such containers effectively without subjecting them to chemical deterioration.

The invention is illustrated in a preferred form in the accompanying drawing, in which the figure is a detail elevation partly in vertical section of a typical container.

Referring to the drawing, a soaking drum 2 is shown as of a form generally employed for the treatment of oil by processes in which detention while hot in a still or agitated pool is required, oil being slowly fed to the drum 2 from a tubular heater in which it reaches an effective temperature for cracking through a lower induct opening, not shown, and being withdrawn at substantially same rate, so as 75 to allow sufficient time to permit desired reactions to take place. The temperature of the oil in the drum may be in the neighborhood of 800° F., although any temperature from 500° to 900° F. may be employed. The 80 drum 2 may comprise flanged educt nipples 21, 21 for customary connections, which openings according to this invention may be closed by suitable caps 22, 22. The heavy domed end of the drum 2 at 23 is usually integral 85 with a flanged manhole extension 20.

When educt pipes at 21 and a closure cap on extension 20 were employed, the upper end of the drum 2 and the interior of the cap 23 necessarily were used to provide a vapor expansion chamber, which was of an unnecessarily large volume. In this space the interior surfaces were corroded most actively.

For the purposes of the present invention, I prefer to make certain that the interior of 95 the drum 2 and its integral extension 20 are covered by the liquid contents, and for this provide for lifting the upper level of the oil pool well beyond the drum 2, domed end 23, and, if desired, as far, for example, as the 100 level α , α , by providing as a separable entity an educt connection, expansion chamber, and relief pipe connection, as shown made as an integral dome 4 surmounting the extension 20, flanged at 18, and fastened as by the heavy 105 bolts 16 to the flange 20. This separable part 4 may be a heavy integral steel casting having a flanged nipple 6 for an educt pipe 8 suit-

ably supported by webs 7 and 9, if desired, and having at its upper end 10 a flanged nipple to receive a safety or relief valve 12, of any usual type suitable to blow at heavy pressures. The casing of valve 12 may provide, as shown, a convenient connection for the vapor relief pipe 14 for taking off the overflow gases, if any, at excessive pressures.

The removable extension 4 thus contains the region in which corrosive action may be expected, and being relatively a much less massive object than the drum 2, may be made of materials or treated as to its inner surface so as to provide a longer life than the upper part of drum 2 could be expected to have. Dome 4 may be made of an alloy steel of superior resisting power, for example, or it may be provided with an electroplated or otherwise coated interior surface of relatively inert material. If and when deteriorated, the dome 4 may be replaced at relatively slight expense of cost and delay, as compared with replacement of the drum 2.

I claim:

1. In a device of the class described, the combination of a container for oil adapted to receive and hold contents at pressures of several hundred pounds to the square inch and temperatures of the order of 450° to 900° F., with means for maintaining the whole interior surface of said container in contact with oil in a liquid state comprising a removable extension at the top of the container into which the liquid oil extends during use of the said container, and means connected with the said extension for drawing off oil therethrough, and an educt passage in said extension communicating with a vapor space in said extension above the oil.

2. In soaking drum apparatus subject to interior corrosion by contained vapors or gases, a soaking drum proper capable of holding a large still or agitated pool of oil under relatively high pressure and temperature, a removable metal extension connected to the

upper end of said container, means having an educt passage for liquid oil forming a part of said extension member, and means in said extension having a vapor passage and adapted to receive a relief valve for relieving excess pressure therein.

3. Soaking drum apparatus comprising a removable integral metallic extension having a side nipple for an educt pipe connection, a flange portion by which said extension may be attached to a soaking drum or other container, and a body portion affording a gas space above said educt connection and having an outlet nipple for oil vapors at substantially the end of said extension opposite its attachment flange.

4. Soaking drum apparatus comprising a removable integral metallic extension having a side nipple for an educt pipe connection, a flange portion by which said extension may be attached to a soaking drum or other container, and a body portion affording a gas space above said educt connection and having an outlet nipple for oil vapors at substantially the end of said extension opposite its attachment flange, in combination with a safety valve casing and valve adapted to be attached to said outlet nipple.

5. In a soaking drum apparatus subject to interior corrosion by contained vapor or gases, a soaking drum proper capable of holding a pool of oil under relatively high pressure and temperature, means at the upper end of said drum for removably attaching an extension of reduced cross section; and a removable metal extension of reduced cross section removably attached to the upper end of said container, said metal extension having therein an educt passage for liquid oil, said extension also having a vapor passage adapted to receive and be closed by a relief valve for relieving excess pressure therein.

Signed by me at Everett, Massachusetts, this 12th day of March, 1927.

HENRY H. HEWETSON
